UNITED STATES PATENT OFFICE.

DANIEL F. LEPLEY, OF CONNELLSVILLE, PENNSYLVANIA.

SLATE-LORRY.

1,129,353.

Specification of Letters Patent. Patented Feb. 23, 1915.

Application filed September 18, 1914. Serial No. 862,389.

To all whom it may concern:

Be it known that I, DANIEL F. LEPLEY, a citizen of the United States, residing at Connellsburg, in the county of Fayette and State of Pennsylvania, have invented a new and useful Slate-Lorry, of which the following is a specification.

The device forming the subject matter of this application is a lorry or conveyer adapted to be employed for handling slate in connection with mining operations and under other circumstances in which a device of the type hereinafter described may be useful.

One object of the present invention is to provide a novel means whereby through the instrumentality of a single element, the gate latch and the gate may be controlled.

Another object of the invention is to provide novel means whereby the gate latch and the gate of the receptacle may be operated, irrespective of the position of the receptacle, when the receptacle is rotated to discharge either in front or at one side of the truck on which the receptacle is rotatable.

Another object of the invention is to provide a device of this type in which all of the controlling mechanisms may be handled by a single operator without changing his position materially upon the supporting truck.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:—Figure 1 shows the invention in side elevation, parts being broken away; Fig. 2 is an end elevation; Fig. 3 is a top plan.

In carrying out the invention there is provided a truck 1 of any desired form and embodying a main frame 2 carrying wheels 3 adapted to traverse a track. The main frame 2 of the truck 1 supports a platform 4.

The invention comprises a suitable means 5 for controlling the brake (not shown), a controller 6 and other appurtenances usually

found upon devices of this type, the elements in question being so located that they may be manipulated conveniently by a person standing on the rear portion of the platform 60. Supported by the main frame 2 and located adjacent the forward end of the machine is an annular track 7 upon which is rotatable a turntable 8 journaled on an upstanding tubular shaft 9 connected at its 65 lower end with the annular track 7 or with any appropriate or convenient portion of the main frame 2. Hinged as shown at 10 to the turntable 8 is a receptacle 11, the bottom 12 of which is downwardly and forwardly inclined. The position of the bottom 12 of the receptacle 11 with respect to the horizontal is adjusted by means of a turnbuckle 14 or an equivalent structure forming an operative connection between the receptacle 11 and the turntable 8, as clearly shown in Fig. 1.

Mounted on the receptacle 11 adjacent the forward end thereof are bearings 15 in which is mounted to rock a horizontally disposed shaft 16. Secured as shown at 17 to the shaft 16 is a vertically swinging gate 18, constituting a closure for the forward end of the receptacle 11. The gate 18 is notched in its edges as shown at 19 to receive keepers 20 and 21 which are secured to the side walls of the receptacle 11. The keeper 20 is equipped with an upstanding lip 22 and the keeper 21 is provided with a depending lip 23. Secured to the gate 18 intermediate its vertical edges, as shown best in Fig. 2, is a yoke 24 carrying a fulcrum pin 25 upon which is pivoted intermediate its ends, for swinging movement parallel to the gate 18, a latch lever 26. One end of the latch lever 26 is adapted to lock behind the lip 23 of the keeper 21 when the said end of the latch lever moves upwardly, and the other end of the latch lever is adapted to lock behind the lip 22 on the keeper 20 when the said end of the latch lever moves downwardly, all of which will be obvious from Fig. 2. The upper edges of the keepers 20 and 21 are beveled as shown at 27, so that when the gate 18 moves downwardly to a closed position, 105 the latch lever 26 will engage automatically with the keepers 20 and 21. Secured to one end of the shaft 16 which supports the gate 18 is a rearwardly extended crank arm 28.

Mounted upon the platform 4 adjacent the rear end of the machine is a supplemental frame 29 in which is journaled a hori-

zontally disposed actuating shaft 30 manipulated through the medium of a crank 31 or its mechanical equivalent. Secured to the actuating shaft 30 is a pinion 32 meshing 5 into a gear wheel 33, the latter being secured to a horizontally disposed shaft 34 journaled for rotation in the supplemental frame 29. Secured to the shaft 34 is a drum 35.

Extended around the periphery of the 10 turntable 8 is a flexible element 36. One end of the flexible element 36 passes rearwardly in tangential contact with a horizontally disposed idler 37 supported upon a standard 38. Thence, the said end of the 15 flexible element 36 passes about a vertically disposed idler 40 journaled on a standard 41 carried by the platform 4. The said end of the flexible element is extended upwardly from the idler 40 and is trained in one direction around the drum 35 on the shaft 34. The other end of the flexible element 36 is 20 trained upon a horizontally disposed idler 39 mounted similarly to the idler 37. From the idler 39 the said end of the flexible element 36 passes about a vertically disposed 25 idler 42 upheld for rotation on a standard 43 and from the idler 42, the end under consideration is trained about the drum 35 in an opposite direction to that end of the 30 flexible element which extends upwardly from the idler 40.

From the foregoing it will be obvious that 35 the flexible element 36 may be actuated by a gear train comprising the shaft 30, the pinion 32, the gear wheel 33, the shaft 34 and the drum 35 to rotate the turntable 8 and consequently to effect a swinging of the receptacle 11 in a horizontal direction, either to the right or to the left of the line of 40 advance of the truck 1.

Journalized in the supplemental frame 29 is an actuating shaft 44, rotated by a crank 45 or the like, the shaft 44 carrying a pinion 46 meshing into a gear wheel 47 secured 45 to a shaft 48 journalized in the supplemental frame 29. Secured to the shaft 48 is a drum 49 to which is secured one end of a flexible element 50. From the drum 49, the flexible element 50 extends downwardly over an 50 idler 51 supported for rotation on a standard 52. From the idler 51, the flexible element 50 extends forwardly in a horizontal direction across the upper edge of an idler 53, the idler 53 being vertically disposed and being journalized on the machine frame. 55 Thence, the flexible element 50 extends downwardly and toward the longitudinal center of the machine around an idler 54, journalized for rotation on the machine frame and inclined with respect to the horizontal, as Fig. 1 will clearly show. From the idler 60 54, the flexible element 50 extends upwardly around a vertically disposed, frame journaled idler 55, the flexible element passing 65 thence upwardly through the tubular shaft

9 and around an upright idler 56 journalized on an angle bracket 57 secured to the bottom 12 of the receptacle 11 and extended transversely of the receptacle. From the idler 56 the flexible element 50 passes around 70 an idler 58 journalized on the laterally protruding end of the angle bracket 57 and from the idler 58 the flexible element extends upwardly around an idler 59 journalized on the rear end of the crank 28 on the shaft 16. From the idler 59 the flexible element 75 extends over an idler 60 carried by the shaft 16, the extremity of the flexible element 50 being downwardly prolonged and being united with a clevis 61 which as shown in 80 Fig. 2, is pivotally connected with one end of the latch lever 26.

The flexible element 50 may be reeled in through the medium of a gear train comprising the shaft 44, the pinion 46, the gear wheel 47, the shaft 48 and the drum 49. When the flexible element thus is actuated, the latch lever 26 is tilted on its fulcrum 25 so as to disengage the opposite ends of the latch lever simultaneously from the keepers 90 20 and 21. A continued pull upon the flexible element 50 will effect a downward swinging movement of the crank arm 28 and a consequent rotation of the shaft 16, the gate 18 being swung to an open position. A 95 single operation, therefore, serves at once to unlatch the gate 18 and to swing the same to an open position. When the flexible element 50 is slackened away, the gate 18 will swing downwardly into the closed position 100 shown in Fig. 1, the opposite ends of the latch lever 20 traversing the beveled edges 27 of the keepers 20 and 21 and ultimately interlocking with the lips 22 and 23 of the respective keepers in a manner which will 105 be entirely obvious when Fig. 1 is compared with Fig. 2.

It is to be observed that the construction 110 of the operating means is such that the gate may be swung to an open position and be closed, irrespective of the angle defined by the receptacle 11 and the line of advance of the truck, the gate operating means being effective when the receptacle discharges toward the front of the machine or laterally toward the sides thereof, it being possible to swing the conveyer to one side or to the other by manipulating the turntable 8 from the shaft 30 and attendant mechanisms, in the manner hereinbefore set forth. Noting 115 particularly Fig. 3 it will be seen that all of the various initial elements whereby the operator controls the movement of the actuated parts are located in compact form near the rear of the platform 4 and within 120 the reach of the operator.

Having thus described the invention, what is claimed is:—

1. In a device of the class described, a truck; a turntable mounted to rotate there- 130

on; a receptacle carried by the turntable; a movable gate for the receptacle; latch mechanism carried by the gate and coacting with the receptacle to hold the gate closed; 5 means for rotating the turntable; a single means operatively connected with the latch for actuating the latch and moving the gate to an open position; and independent mechanisms located to the rear of the receptacle for operating each of said means.

2. In a device of the class described, a truck; a receptacle mounted for rotatory movement but fixed against vertical movement on the truck; a shaft journaled on 15 the receptacle and provided with a rearwardly extended crank arm; a gate attached to the shaft; a latch bar fulcrumed intermediate its ends on the gate; keepers on the receptacle and coöperating respectively 20 with the upper and lower edges of the latch; a flexible element secured to one end of the latch, means on the crank arm for receiving the intermediate portion of the flexible element; and means for actuating the flexible 25 element independently of the movement of the receptacle.

3. In a device of the class described, a truck; a turntable mounted to rotate thereon; a receptacle carried by the turntable; a 30 movable gate for the receptacle; a latch on the gate and coöperating with the receptacle; a supplemental frame on the truck; shafts journaled on the supplemental frame; and flexible elements, one of which elements 35 forms an operative connection between one shaft and the turntable, the other of which elements forms an operative connection between the other shaft and the latch.

4. In a device of the class described, a 40 truck; a turntable journaled thereon; a receptacle carried by the turntable; a gate for the receptacle; a flexible element operatively connected with the gate; means for guiding the flexible element through the 45 turntable at the center of rotation of the turntable; means for actuating the turntable; and means for actuating the flexible element.

5. In a device of the class described, a truck; a turntable journaled thereon; a receptacle carried by the turntable; a gate for the receptacle; a latch on the gate and coacting with the receptacle; a flexible element connected with the latch; means for guiding the flexible element through the 55 turntable at the center of rotation of the turntable; means for actuating the turntable; and means for actuating the flexible element.

6. In a device of the class described, a 60 truck; a turntable journaled thereon; a receptacle carried by the turntable; a shaft mounted to rock on the receptacle; a gate attached to the shaft; a latch on the gate and coacting with the receptacle; a crank 65 arm secured to the shaft; a flexible element connected with the latch; means on the crank arm for receiving the intermediate portion of the flexible element; means for guiding the flexible element through the 70 turntable at the center of rotation through the turntable; means for actuating the flexible element; and means for actuating the turntable.

7. In a device of the class described, a 75 truck; a tubular shaft carried thereby; a turntable rotatable about the shaft; a receptacle carried by the turntable; a shaft journaled on the receptacle; a gate attached to said shaft; a latch carried by the gate 80 and coacting with the receptacle; a crank arm carried by the last specified shaft; a flexible element secured to the latch; means on the crank arm for receiving the intermediate portion of the flexible element; 85 means for guiding the flexible element through the tubular shaft; means for actuating the flexible element; and means for rotating the turntable.

In testimony that I claim the foregoing as 90 my own, I have hereto affixed my signature in the presence of two witnesses.

DANIEL F. LEPLEY.
